3 Claims. (Cl. 121—42)

1

In water turbines, a tendency to hunting of the speed may occur, which hunting may be caused by different conditions but generally by variations in the service conditions and by changes of the delivery of water. This may for instance be the case when two or a plurality of turbines are connected to the same tube line, so that the regulation of one of the turbines will cause variations of the pressure, the magnitude of said pressure variations being dependent upon the position of the guide vane mechanism of the other turbines.

According to the present invention, such hunt-
ings are so suppressed that after a number of hunting half waves, the compensation of the reg-
ulator is changed. The invention further com-
prises means for the indication of the occurrence
of a hunting tendency and the utilization of the
said indication for the changes of the compen-
sation.

According to one form of the invention, the motions of the guide vane mechanism of the turbines caused by the hunttings are utilized for the detection and counting of the hunttings, i. e. for counting of the number of the hunting half waves.

On the accompanying drawing, two different forms of the invention are shown where Fig. 1 shows an arrangement in which the motions of the guide vane mechanism are transmitted to the impulse giving member over an electromagnetic slip coupling whereas Fig. 2 shows an arrangement where polarized relays fed from a potentiometer actuated by the guide vane mechanism serve as impulse giving members to the counting member, which in the form shown in Fig. 1 as well as in the form shown in Fig. 2 suitably consists of a stepping relay.

The present arrangement is applicable to a control mechanism of the type shown in the patent to Lilja, No. 2,273,407.

In the illustrative embodiment shown in the drawing, the invention is incorporated in an hydraulic governor of the type shown in the patent to Lilja, No. 2,273,407. This governor, indicated generally at 105, is used for controlling the speed of a water-wheel turbine 106 actuating a generator 107 which supplies electric current to a network on which a load 109 is imposed. As usual, the turbine speed is regulated by a pen-
stock valve 110 which is adjusted, usually through intermediate hydraulic mechanism (not shown), with a rod 111 of a servomotor 1. Herein, the latter comprises a piston 112 mounted on the rod 111 and reciprocable in a cylinder 113 and prefer-
ably urged in the speed-decreasing direction by a compression spring 114.

2

The governor proper comprises a head 115 carrying flyballs 116 and driven from the turbine prime mover 106 through a connection indicated by a broken line. The flyballs are urged inwardly by a coiled spring 118 which may be adjusted through a screw 119 to vary the gover-
nor speed setting. The position of the flyballs determines the axial position of a pilot piston 120 with respect to a port 121 in a sleeve 122 which is slidable axially in a valve body 122a and has a port 123 communicating through a conduit 124 with a source of pressure fluid. The lower end of the valve cylinder 123 has an outlet through a port 130 and a passage 131. Pressure fluid flows to and from the upper end of the servo cylinder 113 through a passage 132 connected to the port 121.

The mechanism usually employed to compen-
sate for the lag of the prime mover and of the
control system so as to prevent hunting includes
a sleeve 122 which carries a piston 133 reciproca-
ble in a receiving cylinder 134 and urged by a
spring 135 toward a neutral position. A trans-
mitting piston 136 moves with the servo piston
112 to cause oil trapped in the lower end of the
piston cylinder 137 to flow to and from the receiv-
ing cylinder 134 through a passage 138 having a
leak port 139 therein adjustable by a needle 140.
The valve chamber has an outlet 141.

The arrangement thus far described is typical
of the compensating type of hydraulic governor
controls to which the present invention is partic-
ularly applicable.

A supplementary compensating means includes
an hydraulic actuator connected in the fluid com-
pensating circuit and operable to vary the pres-
sure therein instantaneously in response to load
changes. The actuator herein shown comprises
a third cylinder 143 the head of which leads to
the compensating chamber through a passage
144, the connection being to the cylinder 137 in
the present instance. A piston 145 in the cylin-
der 143 is urged in a pressure increasing direction
by a spring 146 and the piston rod 147 is con-
nected to an electric actuator 148 the energiza-
tion of which varies with changes in the load on
the generating system. In Fig. 1, the actuator
comprises an armature 149 on the piston rod
coating with a solenoid coil 150 which is con-
nected to the secondary of a transformer 151
having its primary interposed in one of the lines
leading from the generator 107 so as to be ener-
gized constantly.

The load compensating mechanism described
above is also provided with means for adjusting

the amount of compensation. To this end, a rheostat 153 is connected in parallel with the secondary of transformer 151 or, in the case of the D. C. system, in series with the solenoid. By adjustment of this rheostat, the change in energization of the electric actuator 148 for a given load change may be varied as desired. By opening a switch 154, the load compensator may be disabled completely.

The rod 111 of the servomotor 1 of the regulating apparatus is provided with a second rack 2 with which a pinion 3 engages. The latter is coupled to an electromagnetic slip coupling consisting of the two movable members 5 and 6, of which the member 5 is coupled with the pinion 3 whereas the member 6 is actuated by springs 7 and 8 and is provided with a contact arm 9 with a contact 10 which in the end positions alternatively closes the contact pairs 11 and 12. When these are closed, a current impulse traverses the coil 13 of the stepping relay 14. The armature 15 of this relay which is actuated by the coil 13 is connected with a pawl 16 which for each impulse steps the ratchet wheel 17 a step forward. The pawl 16 is normally out of engagement with the ratchet wheel 17, being held up by an armature 18 actuated by a coil 19 and the current through this coil will be interrupted when the contact 20 in the relay 21 is opened, when the relay coil 22 of this relay receives current which will occur simultaneously with the current delivery to the coil 13. Relay 21 is by means of the condenser 23 delayed in the opening motion in order to enable a plurality of stepping motions following closely after each other. After a certain number of impulses for instance three, which number generally will be sufficient to indicate the existence of a hunting, the contact arm 24 of the ratchet wheel 17 will have moved so far that it will have closed the contact pair 25 thus closing a circuit through the coil 26 in a relay 154 which will perform the change of the compensation. The pressbutton 28 serves for restoring the compensation to its original value after the cause of the hunting has disappeared or been removed.

In Fig. 2, 1 also designates the servomotor of the regulating apparatus which in this case acts on the sliding contact 30 on the potentiometer 31.

The contact 30 is connected over a condenser 32 with the coils 33 and 34 in two parallel-connected polarized relays 35 and 36, the contacts 37 and 38 of which are connected in parallel with the coils 13 and 22 in the stepping relay 14 and time lag relay 21, such as shown in Fig. 1. Instead of using two polarized relays, it is, of course, also possible to use a single relay and then either a polarized relay with two parallel-connected contacts, which are closed alternatively, or a single non-polarized relay, if the latter is sufficiently sensitive.

We claim as our invention:

1. A servomotor system for regulating a water turbine for a power station having compensating means for the said regulator, means for altering said compensating means on occurrence of a hunting, comprising an electric current control device actuated by the servomotor of the system, an electro-magnetic device energized over said control device in response to reciprocating motion of said servomotor, pawl and ratchet mechanism operated by said electro-magnetic device, a time delay electro-magnet controlling the engagement and disengagement of said pawl and ratchet mechanism, and a contact member operated by said ratchet to alter the said compensation.

2. Means according to claim 1, in which the said current control device comprises an electromagnetic slip coupling and a contact arm actuated thereby.

3. Means according to claim 1, in which the said current control device comprises a potentiometer and a sliding contact therefor.
